UNITED STATES PATENT OFFICE.

FREDERICK DIETZ, OF NEW YORK, N. Y., ASSIGNOR TO THE R. E. DIETZ COMPANY, OF SAME PLACE.

LAMP-BURNER.

SPECIFICATION forming part of Letters Patent No. 575,776, dated January 26, 1897.

Application filed February 7, 1896. Serial No. 578,378. (No model.)

To all whom it may concern:

Be it known that I, FREDERICK DIETZ, a citizen of the United States, residing at New York, in the county and State of New York, have invented a new and useful Improvement in Lamp-Burners, of which the following is a specification.

This invention relates to the burner-sockets of lamps, and has the object to prevent, so far as possible, the leakage of oil between the burner and its socket and to insure the return of the oil to the oil-pot in case any leakage should take place. In some kinds of lamps, particularly in driving-lamps, a great deal of annoyance has been experienced by the oil working up through the collar in which the burner is seated. Various attempts have been made to overcome the difficulty, but so far these attempts have not been successful.

In the accompanying drawings, Figure 1 is a sectional elevation of an oil-pot and burner, showing an embodiment of my invention in which the burner is seated upon two washers in the burner-socket. Fig. 2 is a fragmentary vertical section, on an enlarged scale, of the same construction. Fig. 3 is a top plan view of the burner-socket, corresponding in scale with Fig. 1. Fig. 4 is a fragmentary sectional elevation of the burner-socket, burner, and oil-pot, showing an embodiment of my invention in which the burner is seated upon a washer in the lower end of the burner-socket. Fig. 5 is a fragmentary sectional elevation of the same construction on an enlarged scale. Fig. 6 is a fragmentary sectional elevation of the burner-socket, burner, and oil-pot, showing an embodiment of my invention in which the burner is seated upon a washer on the shoulder of the burner-socket. Fig. 7 is a fragmentary sectional elevation of the same construction on an enlarged scale. Fig. 8 is a fragmentary sectional elevation illustrating an embodiment of my invention in which projections and depressions are substituted for the screw-threads of the burner and socket.

Like letters of reference refer to like parts in the several figures.

A represents a burner of ordinary construction provided with the usual lower cylindrical portion *a*, which is connected by a horizontal shoulder or offset *a'* with the screw-threaded

lower portion *b* of smaller diameter and having the usual wick-tube *c* and cone *C*.

D represents an oil-pot of ordinary construction.

E represents the burner-socket, which is secured in the opening in the top of the oil-pot in the usual manner. The burner-socket is provided with an internally-screw-threaded portion *f*, which receives the externally-screw-threaded lower portion *b* of the burner. At the upper end of the screw-threaded portion *f* of the socket is provided with a horizontal annular portion or shoulder *g*, which extends outwardly to a greater or less distance beyond the outer surface of the cylindrical unthreaded portion *a* of the burner, and from that horizontal portion *g* rises an upright cylindrical wall *h* to a greater or less height. This cylindrical wall or upper portion of the socket is separated from the cylindrical portion *a* of the burner by an annular space *i* and forms a drip-cup around the burner.

In the constructions shown in Figs. 1, 2, 3, 6, and 7 a washer *j*, of leather or other suitable material, is arranged on the horizontal portion or shoulder *g* of the socket, and the junction of this shoulder with the cylindrical top portion of the socket is formed with an outward bulge *k*, forming an internal recess, into which the marginal portion of the washer is expanded by screwing the burner down and whereby the washer is securely held in the socket.

The cylindrical top portion of the socket is preferably provided with a small outwardly-turned flange *l*, which forms a rest for the wick-raiser shaft *m*. The wick-raiser shaft has usually a little vertical play in the burner, which is objectionable. When the burner is screwed down upon its seat or seats in the socket, the wick-raiser shaft finds a support on the drip-cup on opposite sides of the burner, whereby the shaft is steadied and the objectionable play is avoided and the burner-shaft is prevented from turning easily, so that the wick cannot jar down when the burner is used in a carriage-lamp. The top flange of this drip-cup, which is preferably employed, forms a flat rest for the shaft and is in that respect more desirable as a support for the shaft than the upper edge of the cup.

In the constructions shown in Figs. 1, 2, 3,

4, and 5 the burner-socket is provided at its lower end with an inwardly-turned flange *n*, on which rests a washer *O*, upon which the lower end of the burner seats itself.

5 In the construction shown in Figs. 4 and 5 the washer on the shoulder *g* of the burner-socket is omitted.

In the construction shown in Figs. 6 and 7 the flange and washer at the lower end of the 10 socket are omitted.

In all of the constructions shown the burner-socket is provided with a horizontal shoulder or flange on which the burner is seated, and which seat is packed by an interposed washer, so that the liability of oil working up through the joint between the burner and socket is reduced to a minimum, and in all of these constructions the burner-socket is provided with an upwardly-projecting wall 15 which surrounds the burner at a short distance outwardly therefrom, and which forms a drip-cup which receives and holds any oil which may accidentally work up through the joint between the burner and socket. In 20 lamps of this class the burner is removed from the socket for filling the lamp, and upon so removing the burner any oil which may have collected in the drip-cup returns to the oil-pot.

30 The construction represented in Figs. 6 and 7 is the simplest embodiment of my invention and is most easily constructed, because the inwardly-projecting flange at the lower end of the threaded portion of the socket is 35 omitted. On the other hand, the construction represented in Fig. 1 is somewhat more oil-tight, owing to the use of two sets of contact shoulders and washers, forming two tight joints between the burner and socket.

40 The screw-threads in the sockets and on the burner may be replaced by other and equivalent devices by which the burner can be forced down upon its seat or seats. For instance, as shown in Fig. 8, the socket may 45 be provided with internal studs or projections *p* and the burner with cam-shaped or inclined depressions *q*, which will answer the same purpose.

I claim as my invention—

1. The combination with an oil-pot and a 50 screw-threaded burner, of a burner-socket having a screw-threaded lower portion which receives the threaded portion of the burner, a horizontal shoulder extending outwardly from the upper end of said screw-threaded 55 portion, a cylindrical upper portion surrounding the burner at a distance therefrom, an external bulge forming an internal annular recess and arranged at the junction of said shoulder with said upper portion of the 60 socket, and a washer resting on said shoulder and confined with its marginal portion in said recess, substantially as set forth.

2. The combination with an oil-pot and a 65 screw-threaded burner, of a burner-socket having a screw-threaded lower portion which receives the threaded portion of the burner, a horizontal shoulder extending outwardly from the upper end of said screw-threaded 70 portion, a cylindrical upper portion surrounding the burner at a distance therefrom, an external bulge forming an internal annular recess and arranged at the junction of said shoulder with said upper portion of the 75 socket, a shoulder extending inwardly from the lower end of said screw-threaded portion, a washer resting on said upper shoulder and confined with its marginal portion in said recess, and a washer resting on said lower shoulder within the lower threaded part of 80 the socket, substantially as set forth.

3. The combination with an oil-pot and a burner having a wick-raiser shaft which projects on both sides beyond the cylindrical 85 wall of the burner, of a burner-socket secured to said oil-pot and having its upper portion composed of a cylindrical wall which surrounds the burner at a distance therefrom and upon which the wick-raiser shaft rests on both sides of the burner, substantially as 90 set forth.

Witness my hand this 4th day of February, 1896.

FREDERICK DIETZ.
